MOP

John Glover, Chicago, Ill., assignor, by mesne assignments, to Midway Chemical Co., Jersey City, N. J., a corporation of New Jersey

Application January 2, 1937, Serial No. 118,833

11 Claims. (Cl. 15—152)

This invention relates to mops.

Among the objects of my invention are to provide a mop which will provide a more effective flat surface pressing downwardly over a relatively large area against the mop cloth when in use; to provide a mop wherein a sheet of metal provides a relatively large, relatively rigid presser plate for engaging the mop cloth over a relatively large area for pressing against the floor or other surface to be mopped and wherein the sheet of metal is provided with an integral jaw member cooperating with a relatively shiftable jaw member between which the mop cloth is clamped; to provide a mop head formed of an integral piece of sheet metal having a connection for the mop stick socket and wherein the sheet metal is provided with struck-up sections which form a mop jaw, hinge portions for connection to the stick socket and guides for the cooperative mop jaw and, in addition, provides a relatively large presser plate over which the mop cloth extends, and which presser plate serves to provide a relatively large surface for pressing the mop cloth against the surface to be cleaned; to provide a mop head which is formed with a single pivotal connection between itself and the mop stick and which pivotal connection is also utilized as a pivotal connection with the jaw clamping and releasing means; to provide a mop wherein the jaw releasing actuator may be shifted into released or clamping position while the mop is in operating position, as when mopping a floor; to provide a jaw releasing mechanism for a mop wherein the shifting of the releasing member is independent of the position of the mop stick; to provide an adjusting member between the shiftable jaw sections of the mop and the actuatable clamping mechanism which is quickly shiftable to various set positions to accommodate variant thicknesses of mop, which construction cooperates in compact relationship with the mop releasing actuator; to provide a mop head wherein the shiftable clamping jaw is pushed upwardly in a toggle-like action to clamping position, as distinguished from being pulled into clamping position; to provide these and other objects of invention as will be apparent from a perusal of the following specification when taken in connection with the accompanying drawing, wherein:

Figure 1 is a perspective view of a preferred form of my improved mop;

Figure 2 is a side sectional view thereof;

Figure 3 is a section on line 3—3 of Figure 1;

Figure 4 is an enlarged view of the jaw adjusting mechanism; and

Figure 5 is a section on the line 5—5 of Figure 4.

In general, my improved mop comprises a mop head having a jaw, a cooperative jaw member with means to produce relative movement between said jaw members for the insertion, clamping and withdrawal of a cloth mop from the head, a mop stick socket having a pivotal connection to the mop head, a jaw clamping actuator preferably provided with means for adjusting the relative movement between the jaws, and lastly while not necessarily, a wringer attachment for cooperation with the cloth or fabric 15 mop when in position on the mop head.

In order to provide a simple, economically constructed and assembled mop, one having few parts, of cheap manufacture and assembly, and one having simplicity and efficiency in operation, I prefer to form the mop head of a single piece of sheet metal 2 having an extended, preferably substantially, but not necessarily, square shape. This surface is flat on the bottom, as shown in Figure 3. The front edge of the flat 25 plate 2 is formed in any desired manner to provide a jaw 4. In the present instance the jaw is formed by curling the front edge over, upwardly, and then inwardly in overhanging relation to the upper side of the plate 2. At the ends the curved-over portion is notched as at 6 and 8 to receive the ends of a cooperating jaw.

This cooperating jaw member is preferably formed and arranged in connection with the mop head 2 so that it nests clampingly within the 35 curled-over jaw portion 4 of the presser plate. Specifically, I prefer to arrange the jaw so that it is pushed into clamping engagement, and I prefer to arrange and to form it of heavy gauged wire bent substantially in the form illustrated 40 in Figure 1. This jaw is illustrated at 10 in the drawing and is shown as provided with opposed free ends 12 and 14 which slide in holes in 45 upstanding ears 16 and 18 struck up from the metal of the presser plate 2. An actuator in the form of a bar 20 is provided with a hole through which the jaw 10 passes to provide an actuating connection.

Means is provided for pivotally attaching a stick socket 22 to the presser plate 2. To accomplish this, I preferably provide from the presser plate two struck-up ears 24 and 26 formed integrally from the metal of the plate. These ears are provided with registering perforations to which the furcations 28 and 30 of the stick socket 55

are pivotally riveted, as at 32 and 34. The stick socket is formed of sheet metal in any approved fashion to receive and clampingly hold the end of the mop stick, whereby the stick may shift from 5 a pivotal position lying somewhat in the plane of the presser plate to a position at right-angles thereto.

In addition, I prefer to utilize the pivots 32 and 34 for pivotally mounting the jaw actuating lever 10 36. This lever is made out of a single piece of sheet metal folded upon itself as at 38, and provided with outstanding ears 40 and 42 for engagement with the fingers. From the folded portion 38 there extends rearwardly two spaced 15 apart arms 44 and 46 which spread outwardly and rearwardly as at 48 and 50 and are pierced for pivotal connection to the pins 32 and 34, respectively.

The portion 44 of this actuator is provided 20 with an opening for the reception of a cross-pin 52. This cross-pin is provided with an enlarged end 54 and a spring 56 which bears against the head of the cross-pin, normally urging the enlarged end 54 into position to engage a number 25 of spaced-apart enlarged holes 58 in the connector bar 20. A narrower slot 60 joins each one of the holes, and the width of this slot corresponds with the diameter of a smaller shank of the pin 52, so that when the head is pushed 30 inwardly the smaller shank will slide along the holes into whichever one is selected, but when the head of the shank is released or pushed outwardly by the pin, the enlarged end 54 will enter the slot and thus hold the members 20 and 44 35 in such selectively adjusted position. By means of this construction, the clamping throw of the jaw 10 relative to the stationary head 4 may be adjusted for mop fabrics of variant thicknesses.

The margin of the presser plate is preferably 40 provided with a channeled portion 55 for strength or neatness and may be provided with one or more slots at 62 for lightness. It will be noted that, by reason of my improved construction, the jaw shifting mechanism of the mop head is constantly accessible and may be quickly and easily 45 operated, irrespective of the position of the mop stick, that is, whether or not the mop stick socket is in substantially right angular position with respect to the plate 2 or is in a common plane therewith. It will also be appreciated that the mechanism for adjusting the throw of the clamping jaw is likewise readily accessible.

By reason of the foregoing, it will be seen that I have provided a most economical type of arrangement wherein a flat sheet metal plate is utilized to provide an extended broad flat surface for receiving and spreading out the mop fabric and for pressing the mop fabric against the floor or other surface to be mopped and, in addition, I have utilized this sheet metal plate to economically form one of the jaw members. I have also utilized struck-up portions of this plate to form bearings or guides for the shiftable jaw member and for providing a pivotal connection, 65 not only for the mop stick, but also for the jaw actuator. It will also be seen that I have utilized a common pivot for attaching the jaw actuator and mop stick to this plate or jaw.

This type of construction readily adapts itself 70 to a type of mop wherein the stick is provided with a mop wringing mechanism, and in the present instance I have provided the stick socket 22 with an aperture for receiving a shank 64 of heavy wire or the like, one end of which is provided with a crank 66 having a handle 68, and

the other end of which is bent in the form of an oblong bow 70 through which the fabric mop 72 is looped, as shown in Figure 2, the other end of the fabric mop being looped over the stationary jaw 4 of the mop head and clampingly held therein by means of the shiftable jaw 10. The mop wringer handle and bow portion 70 are held in desired position by means of a coiled spring 74 which acts against the cross section of the bow 70 and against the side of the stick socket 22. 10 Inasmuch as the shank portion 64 of this mop wringer passes through the socket and the stick, it holds them in assembled position. The spring 74 serves to hold the mop wringer handle 68 in out of the way position. When it is desired to wring 15 the mop, the wringer handle is turned which winds the mop spirally with relation to its clamped position between the jaws whereby to wring out moisture and water from the mop.

Having thus described my invention, what I 20 claim as new and desire to secure by Letters Patent of the United States is:

1. A mop, including a flat sheet metal plate, provided with a jaw member forming an integral part thereof, a second jaw member shiftable co-operating with said first jaw member, said flat plate having integral struck up ears, a stick socket pivotally connected to said ears, jaw actuating means pivotally connected to said struck-up ears by the same pivot that pivotally 30 mounts the stick socket to the rears, and a connection between said actuating means and said shiftable jaw.

2. A mop including a flat plate having an integral jaw portion, a shiftable cooperating jaw portion, guides struck up from the flat plate adapted to slidably receive extensions of the shiftable jaw portion, said flat plate having a pair of struck-up ears, a stick socket, and a shiftable jaw actuating means, common means for 40 pivoting the stick socket and jaw actuating means to the spaced struck-up ears, and a pivotal connection between the jaw actuating means and the shiftable jaw.

3. A mop, including a flat sheet metal plate having its forward edge curled inwardly to provide a jaw, a shiftable jaw nesting within the curled portion of the metal plate and having rearward extensions, guides carried by the upper surface of the sheet metal plate to slidably receive the 50 jaw extensions, an actuator pivotally connected at the central portion of said shiftable jaw, a stick socket connected to the rear portion of the plate, and a lever pivotally connected to said plate and to said actuator.

4. A mop including a flat sheet metal plate having its forward edge curled inwardly to provide a jaw, a shiftable jaw nesting within the curled portion of the metal plate and having rearward extensions, guides carried by the upper surface 60 of the sheet metal plate to slidably receive the jaw extensions, an actuator pivotally connected at the central portion of said shiftable jaw, a stick socket connected to the rear portion of the plate, a lever pivotally connected to said plate, and means providing an adjustable connection between the lever and said actuator to vary the 65 throw of the shiftable jaw relatively to said stationary jaw.

5. A mop comprising a sheet metal plate provided with an integral fixed jaw portion, a shiftable jaw mounted on the upper surface thereof for sliding movement toward and from said jaw portion, a stick socket pivotally connected to said plate, a lever pivotally connected to said plate, 70

an actuator pivotally connected to said lever and to said shiftable jaw for pushing the jaw into clamping engagement with said stationary jaw.

5. 6. A mop, including a sheet metal flat plate having its front surface curled upwardly and inwardly to overhang the upper surface of the plate, a wire jaw bent nestlingly to lie within the overhanging portion of the first-mentioned jaw, 10 said jaw having two rearwardly extending ends, tabs struck upwardly from the sheet metal plate and perforated to slidably receive the wire ends of the jaw, an actuator pivotally connected to the central portion of the jaw, and a lever 15 mounted on said plate and pivotally connected to said actuator whereby on movement of said lever the jaw is moved toward and from the stationary jaw.

7. A mop, comprising a flat sheet metal plate 20 of relatively large area, said plate having its front edge curled upwardly and inwardly in overhanging relation to the upper surface of the plate to receive a fabric mop, the mop extending over the curved front edge and beneath the sheet metal plate, a jaw shiftingly mounted on the upper 25 surface of the sheet metal plate and having its front edge adapted nestingly to fit within the overhanging portion of the stationary jaw, and actuating means mounted on the upper surface 30 of the sheet metal plate and connected to said jaw for shifting it to clamping or releasing position, and a stick socket pivotally connected to said plate.

8. A mop comprising a sheet metal plate having 35 a jaw, a pair of sheet metal ears struck upwardly from the plate in spaced relation, a stick socket pivoted to said ears, a lever formed of a single piece of sheet metal having spaced-apart legs pivoted to said ears, the forward end of said lever being provided with a finger piece, and a pair of 40 registering perforations, a jaw cooperating with the first-mentioned jaw, an actuator pivoted thereto, said actuator being provided with a plurality of holes connected by smaller slots, a transverse pin pivotally interconnecting the registering 45 perforations in the lever with the slots and holes in the actuator, said cross-pin having an enlarged head and a narrow shank, spring means for urging the enlarged head into position to pivotally

interconnect the lever with one or more of the holes in the actuator, the narrower slots interconnecting the holes being sufficient in size to freely receive the narrower shank of the pin when the same is pushed into registration therewith. 5

9. In a mop, the combination of a sheet metal plate having its front edge formed as a jaw, a second jaw mounted on the top of said plate and adapted slidably to engage said plate to move toward and from the first-mentioned jaw, a stick 10 socket pivoted to the uppermost portion of said plate at the rear thereof, an actuator connected to said second jaw, a lever pivotally connected to said plate and extending forwardly of the pivotal connection between the stick socket and the plate, 15 and a pivotal connection between the lever and the actuator, the forward portion of said lever being provided with a portion to be grasped by the fingers.

10. In a mop, the combination of a sheet metal 20 plate having its front edge formed as a jaw, a second jaw mounted on the top of said plate and adapted slidably to engage said plate to move toward and from the first-mentioned jaw, a stick 25 socket pivoted to the uppermost portion of said plate at the rear thereof, an actuator connected to said second jaw, a lever pivotally connected to said plate and extending forwardly of the pivotal connection between the stick socket and the plate, and a pivotal connection between the lever and 30 the actuator, the forward portion of said lever being provided with a portion to be grasped by the fingers, said pivotal connection between said lever and said actuator having means for varying the throw of the jaw upon predetermined movement of the lever. 35

11. A mop including a flat sheet metal plate provided with a fixed jaw member upstanding from the surface of the plate adjacent an edge thereof, a shiftable jaw member slidably mounted on the 40 upper surface thereof cooperating with said first mentioned jaw member, a stick socket pivotally connected to said plate, jaw actuating means pivotally connected to said plate, said jaw actuating means comprising a toggle actuatable in a 45 plane transverse to the plane of said plate and a connection between said actuating means and said shiftable jaw.

JOHN GLOVER.
